UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

BRICK MACHINE AND METHOD OF OPERATING THE SAME.

Application filed August 20, 1925. Serial No. 51,287.

To all whom it may concern:

Be it known that I, HOWARD K. KING, a citizen of the United States, residing at Philadelphia, in the county of Philadelphia, 5 State of Pennsylvania, have invented a new and useful Improvement in Brick Machines and Methods of Operating the Same, of which the following is a specification.

My invention relates to improvements in 10 brick machines. The object is to provide improvements in the bar cutting mechanism, so that all the cuts shall be in parallel planes.

In machines of the type described in my 15 Patent No. 1,178,930, dated Apr. 11, 1916, it has been found that the bar of material which is cut into separate bricks, has a tendency to expand toward its outer end, especially when the bar is composed of shale or similar material. This tends to cause 20 the cutting wires to sever the bar in distorted planes, so that some of the bricks are not cut in strictly parallel planes. I have found that by clamping the forward end of the bar as it assumes its position on the 25 cutting platens, this tendency to expand is counteracted and a true cut of all the bricks is assured.

Referring to the drawings, which illustrate merely by way of example suitable 30 means for effecting my invention:—

Fig. 1 is a fragmentary end elevation of the reel frame, showing my improvement.

Fig. 2 is a fragmentary side elevation.

Fig. 3 is a similar view, showing the parts 35 in different positions.

Fig. 4 is a fragmentary view showing the parts in a still different position.

Similar numerals refer to different parts throughout the several views.

40 In Fig. 1, 5 indicates a portion of the reel housing. 6 indicates a stationary upright or standard. It will be understood that the housing is rotatably fixed but has horizontal reciprocating movement with the reel. 7 represents the cutting platens and 8 the dead plate upon which the cut bricks are delivered. 9 indicates the cutting wires and 45 10 the bar of clay or other material which is cut into bricks by the wires 9. In Fig. 2 the bar is shown in the position upon the cutting platens, in which it is cut by the wires 9. It is when the bar is in this position and during the cutting operation, that it tends to expand toward the forward end, which results in an irregular or distorted cut. To

prevent this undesirable action I provide the following mechanism.

To the housing 5 is secured, by bolts or other suitable means, the frame 11, in which is pivotally mounted, as at 12, one end of the U-shaped frame 13; the other end of this frame being pivotally mounted in the bracket 14, also bolted to housing 5. Integral with frame 13 is the arm 15, having the roller 16 on its outer end. On the frame 13 is adjustably mounted the clamping blade 17, a spring 18 connected between the pivoted frame 13 and the frame 11, normally holds the frame 13 and clamping blade 17 in elevated position above the top plane of 70 the bar 10. The clamping blade 17 is adjustably secured to the angle iron 19 and the angle iron 19 is adjustably secured to the frame 13 by any suitable means, such as by bolts and slots, as shown. A lug 20, secured to an arm of frame 13, is adapted to engage an abutment 21 on frame 11, to limit the spring actuated movement of frame 13.

On the standard 6 is secured the bracket 22, upon which is pivotally mounted, as at 23, the cam 24. The bracket 22 is provided with the lug 25, preferably integral therewith, for limiting the gravity actuated pivotal movement of the cam 24.

In operation: As above stated, the reel 85 housing 5 has a horizontal reciprocating movement; to the left to receive the bar 10, and to the right to move with the bar while the cutting wires 9 are passing through it.

Fig. 2 shows the positions of the parts during the movement of the housing to the right and during the cutting operation with the clamping blade 17 in engagement with bar 10. As the housing 5 completes its movement to the right and after the cutting operation is completed, the roller 16 passes over the end of lug 25, whereupon the spring 18 draws the frame upwardly and the blade 17 into the position shown in Fig. 3.

As the housing 5 now moves to the left to receive a new length of bar 10, the roller passes under cam 24. When roller 16 clears the lower left hand end by cam 24, the cam falls into position shown in Fig. 4, so that, upon the return movement of housing 5 to the right, the roller encounters the inclined face 24' of cam 24 which carries the roller up to the top substantially horizontal face of the cam and consequently brings the blade 17 again into clamping position upon 100 105 110

the bar 10. It will be noted that the top surface of cam 24 and lug 25 inclines slightly upwardly from the left hand end to the right hand end to insure efficient engagement of the clamp 17 with bar 10, during the cutting movement of the housing 5. It will also be noted that the axis 12 of frame 13 is below the top surface of bar 10, so that the engagement of camp 17 with bar 10 serves effectually to counteract any tendency to further relative movement between the bar 10 and the cutting platens and cutting wires.

It should also be noted that the extreme right hand end of bar 10, which extends beyond the last cutting wire 9, varies in dimension and is therefore discarded as waste or defective. As this end piece will sometimes approach the full or regulation thickness of the brick, it cannot always be readily recognized by the operatives, and hence there is a tendency for some of these defective end-pieces to slip through to the kiln and thus make trouble. By observing the mark upon this end-piece, made by the clamping plate 17, which always engages the bar near the extreme end, and therefore within the area of the end-piece, said defective end-piece becomes readily distinguished, so that the danger of overlooking any defective end-piece is thereby eliminated.

What I claim is:

1. The method of preventing distortion in the wire cutting of bars into bricks, which consists in clamping the end of the bar to its moving support during the cutting operation.
2. The method of preventing distortion in the wire cutting of bars into bricks, which consists in automatically clamping the end of the bar to its moving support during the cutting operation.
3. The method of distinguishing defective end-pieces of a bar which is cut into bricks, which consists in producing a visual mark upon the said end-piece before the cutting operation is completed.
4. In combination with bar cutting

mechanism for brick machines, a clamping device and means for actuating the clamping device to engage the bar near the extreme forward end thereof during the cutting operation.

5. In combination with bar cutting mechanism for brick machines, a clamping device and means for actuating the clamping device to engage the bar near the extreme forward end thereof prior to and during the cutting operation.

6. In combination with bar cutting mechanism for brick machines, a clamping device and automatic means for actuating the clamping device to engage the bar near the extreme forward end thereof during the cutting operation.

7. In combination with bar cutting mechanism for brick machines, a clamping device and means for actuating the clamping device to engage the bar near the extreme forward end thereof during the cutting operation, and means for releasing the clamping device from the part of the bar engaged thereby upon the completion of the cutting operation.

8. In combination with bar cutting mechanism for brick machines, comprising a rotatable wire reel and a reciprocating housing therefor, a clamping device mounted on the housing, and means mounted on a stationary part of the machine for cooperating with the clamping device to cause its engagement with the bar near the forward end thereof during the cutting operation.

9. In combination with bar cutting mechanism for brick machines, comprising a rotatable wire reel and a reciprocating housing therefor, a clamping device mounted on the housing, means mounted on a stationary part of the machine for cooperating with the clamping device to cause its engagement with the bar near the forward end thereof during the cutting operation, and means for moving the clamping device out of the path of travel of the bar after the cutting operation is completed.

HOWARD K. KING.
